Wm. Hunter Myers.

UNITED STATES PATENT OFFICE.

THOMAS BRIGHAM BISHOP, OF CLIFTON, NEW JERSEY.

CAR-AXLE LUBRICATOR.

SPECIFICATION forming part of Letters Patent No. 399,369, dated March 12, 1889.

Application filed October 22, 1888. Serial No. 288,752. (No model.)

To all whom it may concern:

Be it known that I, THOMAS BRIGHAM BISHOP, a citizen of the United States of America, residing at Clifton, in the county of Passaic and State of New Jersey, have invented certain new and useful Improvements in Car-Axle Lubricators, of which the following is a specification, reference being had therein to the accompanying drawings.

10 My invention relates to an improved car-axle lubricator; and it consists in certain details of construction and combinations of parts, which will first be described in connection with the accompanying drawings, and 15 then pointed out in the claims.

Figure 1 of the drawings is a longitudinal section of a car-axle box, the lubricating-web and a portion of the car-axle being shown in elevation. Fig. 2 is a transverse section 20 taken on the line $x-x$, Fig. 1, the spring being shown in elevation. Fig. 3 is a detached perspective view of the web, the web-stretching plate, and the spring in position with relation to each other.

25 In the drawings, A indicates a car-axle box; B, the bearing, of usual construction, and C the car-axle.

D represents the web-stretching plate, made of metal. This plate is of a width to fit the 30 interior of the box, so as to avoid lateral movement therein. In the middle it is formed with a concavity, c, to conform to the shape of the axle, and near each end it is slotted, as at s, for the passage therethrough of the web, 35 the plate presenting a broad flat surface between the slots and the edges of the concavity, as clearly seen in Figs. 2 and 3.

E represents the web, which may be of felt or other thick cloth, and it is of the full 40 width of the part of the axle to be lubricated. I make it continuous by joining the ends of the cloth, in order that when one portion becomes worn the web may be turned around to present another wearing-surface, several of 45 which can be thus utilized, as the web is of a length to reach from its position under the axle to and over the bottom of the box. The web is passed through the slots in plate D and pressed down into the concavity, and 50 then its ends are joined. In this position the plate and web are placed in the axle-box. A

coil-spring, S, rests on the bottom portion of the web and bears at its top against the under side of the stretching-plate, in this manner drawing the web smoothly over the concave 55 and flat portions of the plate. Oil being placed in the box will ascend through the web by capillary attraction, and be evenly and continuously distributed over the entire portion of the axle requiring lubrication. 60

As some axle-boxes are deeper than others, I make the spring S of a length suitable for the deepest, and provide it with a hook, h, for hooking up a number of the coils, so as to adjust the spring to the box in which it is to be 65 used.

Having thus described my invention, what I claim as new, and desire to secure by Letters Patent, is—

1. In a car-axle lubricator, the combination, 70 with the axle-box and the axle therein, of a stretching-plate having a concavity in its top and a flat surface on each side of said concavity, a continuous web passing over the top of said plate and the bottom of the box, the 75 axle bearing on that portion of the web within the concavity in the plate, and a spring bearing at the bottom on the web and at the top against the plate, whereby the web is kept smooth under the axle. 80

2. In a car-axle lubricator, the combination, 85 with the axle-box and the axle therein, of a stretching-plate slotted, as described, and having a concavity in its top and a flat surface on each side of said concavity, a continuous web passed through said slots and over the top of the plate, and also over the bottom of the box, the axle bearing on that portion of the web within the concavity in the plate, and a spring bearing at the bottom on the 90 web and at the top against the plate, for the purpose stated.

3. In a car-axle lubricator, the combination, 95 with the axle-box and the axle therein, of a stretching-plate of the full width of the interior of the box, slotted, as described, and having a concavity in its top and a flat surface on each side of said concavity, a continuous web, of the width of the part to be lubricated, passed through said slots and over 100 the top of the plate, and also over the bottom of the box, the axle bearing on that portion

of the web within the concavity in the plate, and a spring bearing at the bottom on the web and at the top against the plate, whereby the web is kept straight and smooth under 5 the axle.

4. In a car-axle lubricator, the combination, with the box and axle, of a stretching-plate for the web, a continuous web passing over the top of said plate and over the bottom of 10 the box, and a coil-spring provided with a

hook for hooking up a number of the coils, the said spring pressing at the bottom on the web and at the top against the plate, as set forth.

In testimony whereof I affix my signature 15 in presence of two witnesses.

T. BRIGHAM BISHOP.
